UNITED STATES PATENT OFFICE.

GEORGE ELDEN HANES, OF DENVER, COLORADO.

AEROPLANE.

1,079,171.

Specification of Letters Patent. Patented Nov. 18, 1913.

Application filed May 23, 1912. Serial No. 699,125.

To all whom it may concern:

Be it known that I, GEORGE E. HANES, a citizen of the United States, and a resident of Denver, in the county of Denver and State of Colorado, have invented a new and Improved Aeroplane, of which the following is a full, clear, and exact description.

This invention relates to improvements in air ships, and particularly to aeroplanes, 10 and has for an object to provide an improved structure in which the balancing mechanism is simplified for quickly restoring the balance or equilibrium to the aeroplane at any time.

15 A further object of the invention is to provide an aeroplane with automatically operating means for causing the aeroplane to recover after the same has been tilted to one side.

20 A still further object of the invention is the provision of an aeroplane in which the lifting plane or planes are pivotally mounted on a bearing shaft which carries a supporting framework for supporting the aeroplane 25 when on the earth, and for supporting the principal parts of the device which have an appreciable weight, whereby the planes may be easily adjusted in respect to the weight carried thereby for causing a variation in 30 the lifting action of the planes for raising and lowering the aeroplane, and for other reasons as occasion may demand.

In carrying out the objects of the invention, a plane is provided formed with a 35 plurality of independent sections arranged in the same horizontal plane. These planes are held properly in position by stiffening ribs and by a suitable depending framework, together with guy ropes or lines. Pivotally 40 mounted centrally of the planes is a journal shaft which carries the framework, including the driving mechanism, operator's seat, skids, and other necessary attachments, including adjustable mechanism engaging the 45 framework depending from the planes whereby the incidence of the planes may be varied.

A practical embodiment of the invention is represented in the accompanying drawings forming a part of this specification, in 50 which similar characters of reference indicate corresponding parts in all the views.

Figure 1 is a top plan view of an embodiment of the invention, one edge of the planes 55 being broken off; Fig. 2 is a side view of the structure shown in Fig. 1; Fig. 3 is an

enlarged detail side view of the rear end of the skid showing an earth-engaging brake mechanism; Fig. 4 is an enlarged detail fragmentary perspective view of part of an adjusting mechanism for varying the angle of the planes; and Fig. 5 is a front view of the structure shown in Fig. 2.

Referring to the accompanying drawings by numerals, 1 indicates a plane in its entirety, 2 the framework for bracing the same, 3 a pivotally mounted frame, and 4 a supporting skid structure. The plane 1, as clearly shown in Fig. 1, is formed of a plurality of auxiliary planes 5 having 60 spaces 6 therebetween, and held in place by suitable bracing ribs 7 and 8, the bracing ribs 7 being formed double and bolted together, or secured together in any other desired manner. Each of the auxiliary planes 70 5 is formed substantially arc-shaped, as clearly shown in Fig. 2, with the exception of the front plane which is formed with a flattened front portion 9 which extends directly to the front and parallel with the 80 earth when the entire plane structure 1 is substantially parallel with the earth. This provides an entering edge 10 for entering the air and causing the various planes 5 to strike against the air in the passage of the 85 machine in flight.

The framework 2 is rigidly connected with the plane 1 in any desired manner, and has the front bar 11 formed so as to pass through the plane 1 at the point 12 for forming a 90 brace or staff 13. An auxiliary bracing rod 14 is provided which extends from the upper end of the bracing rod 13 to the point 15, and from thence down to the rod 11 at the point 16. The rod 13 is designed to 95 have any desired number of guy wires 17 connected therewith for bracing the frame 2, and the plane 1. A rod 18 similar to the rod 11, is provided at the rear of the machine which passes through the frame 2 at 100 19 and forms a rear staff 20 adapted to carry a rudder 21. Connected with the upper end of the staff 20 is a bracing rod 22 which extends in an inclined direction forwardly and passes through plane 1 at the point 23 and 105 from thence down to the rod 18 at the point 24. Connecting the rods 11 and 18, and extending from points 16 to 24, is an arc-shaped bearing member 25, the particular construction of which is better seen in Fig. 110 4 wherein it will be observed that it is formed substantially in the shape of an

I-beam, thus defining grooves 26 and 27. The groove 27 is designed to accommodate the upper edge of an arc-shaped portion 28 of the skid 4. The groove 26 is designed to accommodate a pulley structure 29 over which pass cords 30 and 31. The cord 30 passes over one side of the pulley and then to a point 32, while the cord 31 passes over the opposite side of the pulley 29 and to the point 33 where it is secured. The pulley 29 is mounted upon a shaft 34 which is preferably bent for providing bracing arms 35 and 36 which are rigidly secured or merge into a shaft 37 which carries the traction wheels 38 and 39. The shaft 37 is continually maintained a short distance above the arc-shaped bearing member 25 so as to permit a free back and forth movement of the arc-shaped bearing member 25 in respect to the skid 4 and associated parts. The cords or cables 30 and 31 extend upwardly from the spool or pulley 29 and are reversely wound on the drum 40 held in place by suitable brackets 41. The shaft 42 of the steerage wheel 43 is connected by a universal joint 44 to the drum 40 so that whenever it is desired to shift the angle of incidence of the plane 1 the steerage wheel 43 is moved for winding one of the cords 30 or 31 and unwinding the opposite cord whereby the skid 4 and associated devices will be shifted longitudinally of the bearing member 25 and consequently will cause a shifting of the center of gravity, thus resulting in tilting the planes in either direction. Before the shaft 34 is bent to form the bracing arms 35 and 36, the same is passed through a bracing standard 45 which is rigidly connected at 46 to the skid 4. This permits a proper fulcrum action between the cords 30 and 31 and associated parts and the skid, so as to move or rather tilt the aeroplane in respect to the skid 4, the skid 4 and associated parts by their weight resisting any swinging movement.

The skid 4 has rigidly secured thereto not only the bracing standard 45, but the bracing standard 47 which extends upwardly and is pivoted to a cross journal 48. The cross journal 48 is mounted upon suitable bearings carried by the bracing ribs 7 and 8. The bracing standard 47 is pivotally mounted on the shaft 48, while the standard 45 is rigidly secured to a supporting framework 49 to which is secured the engine 50. The framework 49 is pivotally mounted at 51 on the shaft 48 so that the engine will move or swing with the skid 4. In addition to these members a pair of tubular members 52 and 53 are pivotally mounted on the journal or shaft 48 and extend in an inclined direction downwardly, as shown in Fig. 5. Into these members 52 and 53 are slidingly fitted rods 54 and 55 which are journaled at 56 and 57 on the axle 37. Stops 58 and 59 are

rigidly secured in any desired manner to the bars 54 and 55 so as to properly support the springs 60 and 61. The springs 60 and 61 bear at one end against the stops just described and at the opposite ends against the lower ends of the two members 52 and 53. By this construction and arrangement the springs are designed to take up any shock in landing as the same will permit the bars 54 and 55 to telescope therein against the action of the springs 60 and 61. If the shock in landing is very great the springs will be compressed until the skid 4 engages the earth for substantially its full length and then the skid will take the remaining part of the shock. Pivotaly mounted on the journal or shaft 48 is an operator's seat 62 which has connected therewith a brace 63 carrying on its lower end a roller 64 designed to fit into the groove 26 for guiding the rear part of the arc-shaped bearing member 25. The shaft 65 which carries the roller 64 extends through the bracing standard 47 so as to properly hold the brace 63 in position. In order to give a better support for the center of the plane 1, and also for the center of the arc-shaped bearing member 25, a pair of bracing rods 66 and 67 are connected with shaft 48 and also in any desired manner at the point 68 to the bearing member 25. Upon the movement of the plane 1, the bracing rods 66 and 67 will move pivotally with the remaining part of the frame 3, while the skid 4, members 45 and 47, and connected parts will remain substantially stationary, the same being held in that position by gravity.

Arranged at the rear of the skid 4 is a brake pin 69 fitting into an aperture 70. The pin 69 is secured to a spring 71 in any desired manner which is connected at 72 to the skid 4. A pivotally mounted trigger 73 is provided which normally holds the spring 72 and pin 69 in an elevated position, as shown in Fig. 3, but is adapted to be moved from beneath the spring 71 whereupon the spring 71 will depress the pin 69 and cause the same to project through the aperture 70 and into the earth. This is what might be called an emergency brake to be used in case the aeroplane cannot be otherwise stopped as soon as desired after alighting. A cable 76 is connected with the trigger 73 and is passed over suitable pulleys to a position near the operator's seat so that the operator can easily release the spring whenever desired.

The rudder 21 has connected therewith cords or cables 77 and 78 which are passed over suitable guiding pulleys or guiding tubes and are secured at 79 to the shaft of the steerage wheel 43, whereby when the steerage wheel 43 is moved laterally the rudder will be correspondingly moved, this movement being made without in any way

affecting the angle of incidence of the plane 1.

Arranged on the upper part of the machine is an automatic balancing mechanism 5 designed to automatically engage the air to a greater or less extent when the device is tilted to one side so as to cause the air pressure on that side and from the front to tend to right or restore the machine to a 10 proper equilibrium. In forming this mechanism, a pair of standards 80 and 81 are provided, which are suitably braced by guy wires 82 which are connected in any desired manner to the members. Pivots 15 mounted on these standards are planes 83 and 84 which are normally set at an angle so that the planes will converge centrally and at a lower point on the frame 3. Bracing rods 85 and 86 are provided for positively holding the planes 83 and 84 from 20 tilting to any greater extent independently of the machine. However, these planes, including the bracing rods 85 and 86, are permitted to pivot or swing around the standards 80 and 81 freely. A pair of connecting wires or cables 87, are connected to the planes 83 and 84 for causing the same to act together. When the aeroplane is in its correct position the planes 83 and 84 will 25 be in the position shown in Fig. 2, but when tilted to one side the weights 88 and 89 connected to one end of each of the planes will move the planes pivotally, whereby the same is caused to engage the air as the aeroplane 30 continues in flight and by such an engagement will cause a resistance to the flight in such a direction as to tend to right the machine or bring the machine back to an equilibrium. It will be observed that when the 35 machine is moving straight to the front directly without any side tilting, the planes 83 and 84 are edgewise to the line of flight and will not cause an appreciable resistance, but when moved pivotally around the standards 80 and 81 will cause more or less resistance, and consequently a pushing action 40 for bringing the aeroplane back to its correct position. The action of these planes it will be observed, is absolutely automatic and is 45 caused largely by the weights 88 and 89 connected to one end of the planes.

The engine 50 may be of any desired construction and may be controlled in any desired manner, the same being used for driving the propeller 50'.

The wheels 38 and 39 are provided with coaster brake hubs 38' and 39', to the operating arms of which are connected cords

extending to the operator's seat. This arrangement permits the operator to lock 60 either of the wheels so that when on the earth the device may be turned or steered as desired.

Having thus described my invention I claim as new and desire to secure by Letters 65 Patent:—

1. In an aeroplane, a supporting plane formed with a plurality of stiff auxiliary planes constructed substantially arc-shaped in cross section with the exception of the 70 front auxiliary plane which is formed with a straight entering portion, all of said auxiliary planes being arranged in the same plane and extending in the same direction fore and aft, and means for bodily tilting 75 the entire supporting plane for changing the angle of incidence thereof whereby the auxiliary planes are adapted to engage the air, the said auxiliary planes acting as lifting members and increasing said action according to the angle of incidence thereof, propelling means associated with said supporting plane, and steering means.

2. In an aeroplane, a supporting plane, a frame for supporting said plane formed 85 with an arc-shaped lower portion, said arc-shaped lower portion being formed I-shaped in cross section, a gravity actuated frame formed with a bottom having means extending into one of the grooves of said I-shaped 90 lower portion of said first mentioned frame for guiding the supporting plane in respect to the gravity actuated frame, means for propelling, the aeroplane, and means for steering the same.

3. In an aeroplane, a supporting plane, propelling means therefor, steering means, means for changing the angle of incidence of said supporting plane, a pair of pivotally mounted stabilizing planes arranged at a 100° dihedral angle to said supporting plane, a weight secured to one end of each of said planes for causing the same to be actuated by gravity whenever said supporting plane is tilted sidewise whereby the stabilizing 105 planes will resist said sidewise tilting, and connecting members for connecting said stabilizing planes for causing the same to act in unison.

In testimony whereof I have signed my 110 name to this specification in the presence of two subscribing witnesses.

GEORGE ELDEN HANES.
